UNITED STATES PATENT OFFICE

HERBERT S. POWELL, OF UTICA, NEW YORK

MUFFLER FOR INTERNAL-COMBUSTION ENGINES

Application filed May 18, 1928. Serial No. 278,889.

- My invention relates to a muffler for internal combustion engines, and I declare the following to be a full, clear, concise and exact description thereof sufficient to enable any-
5 one skilled in the art to which it appertains to make and use the same, reference being had to the accompanying drawings in which like reference characters refer to like parts throughout the specification.
- 10 The object of the invention is to provide a device that will silence the sound caused by the exhaust gases of an internal combustion engine upon reaching the atmosphere. To this end, the muffler is equipped with expand-
15 ing and contracting chambers and with pockets to aid in decreasing the vibrations of said muffler and also to aid in silencing the noise incident to the exhaust gases escap-
ing to atmosphere.
- 20 The object will be understood by referring to the drawings in which:
Fig. 1 is a central vertical section of the muffler showing parts in full.
Fig. 2 is a central vertical section of a modified form of the muffler.
- 25 Referring to the drawings more particularly, the device embodies a plurality of interfitting cups. The cups are made to interfit by shaping the free edge, with the exception of the first cup, into an annular shoulder 1 adapted to provide a seat for nesting the adjacent bottom edge of the preceding cup. The cups and end members 3 and 5 are held together by stay rods 8, 8. Tube 9 forms
30 an inlet port and is fastened to end member 3 by spinning portions adjacent the end of tube 9 to the edge thereof bordering on the central aperture.
- 35 A cylindrical tube 10 is welded at one end to an annular shoulder 11 formed integral with end member 3 and is adapted to project through the chambers formed by the first two cups 15 and 16 and partly into the chamber formed by cup 17. Tube 10 is in alignment
40 although much larger in diameter than inlet tube 9, whereby to permit the exhaust gases to expand to a certain degree on reaching said tube 10. The bottom surfaces of cups 15 and 16 are cut away to provide large central apertures for the projection of tube
45 10 and to leave a narrow unperforated flange at 14, 14. The annular space between the inner walls of cups 15 and 16 and the outer wall of tube 10 forms a pocket or cushion chamber adapted to decrease the tendency of 55 the muffler to vibrate.
- 50 A conical or funnel shaped member 20 is fastened to the bottom 21 of cup 17 by spinning the upper part thereof to the edge of bottom 21 adjacent the central aperture, 60 whereby the exhaust gases will be contracted before entering the chambers of cups 22 and 23. The bottom surfaces of cup 22 is cut away to provide a large central aperture at 24 and thereby leave only a narrow unperforated flange 25, whereby to permit the exhaust gases to expand through a portion of the chamber of cup 22 and through the chamber of cup 23. Moreover, a conical shaped member 20 is spun to the bottom of surface 65 of cups 23 and 25, whereas cup 24 has a large central aperture 30 and narrow unperforated flange 31, whereby to cause the exhaust gases to expand as above explained in their passage through a portion of cup 24 and cup 25 and then contract while passing through conical shaped member 20 of cup 25. Cup 32 is equipped with a large central aperture leaving only a narrow unperforated flange 37 whereby to allow the exhaust gases to expand 70 into the chamber of cup 33. Cups 33 and 34, however, are equipped with a plurality of small apertures 36 in the bottom surface thereof, in each instance, whereby to further break up and segregate the onrushing exhaust gases. Cup 35 has spun to the bottom thereof a cylindrical open tube 40 for the passage of the exhaust gases to a tube 41 of larger diameter projecting through end member 5 and spun thereto. An open tube 42 of smaller diameter is spun to the end surface 43 of tube 41, whereby to permit the exhaust gases to escape to atmosphere.
- 75 Cup 37 has a large central aperture leaving only a narrow unperforated flange 38, whereby to form an annular pocket or cushion chamber at 43 adapted to allow the exhaust gases to enter by way of annular opening 44 between the inner surface of tube 41 and the outer surface of tube 40, whereby 80
- 85

- 95

to aid in silencing the noise of the escaping exhaust gases and to lessen the vibration of the muffler.

The operation of the muffler is as follows: When the exhaust gases enter the muffler by way of tube 9 they progress through tube 10 to the chamber of cup 17, some rebounding, however, into the annular space between the outer surface of tube 10 and the inner surface of cups 15 and 16 to aid in lessening the vibration of the muffler whence they will be gradually redrawn into the chamber of cup 17 and eventually pass out through conical shaped member 20 with the major portion of the gases into the chamber formed by cups 22 and 23. As the gases pass through conical shaped member 20 they will be contracted to be allowed to again expand on entering the chamber formed by said cups 22 and 23. The alternate process of contraction and expansion will be repeated as the gases progress through the cups 24, 25 and 32, 33 until they reach the bottom surface of cup 33 where they will be broken up and segregated as they pass through the small apertures 36 of cups 33 and 34. Thereafter the exhaust gases will escape to atmosphere through open tubes 40, 41 and 42. A small portion, however, of said gases will rebound into the annular chamber or pocket 43^a formed between the outer surface of tube 40 and the inner surface of cups 37 and 45, by way of annular opening 44 between the outer surface of tube 40 and the upper inner surface of tube 41, to form a cushion to aid in silencing the noise of the exhaust gases as they pass to atmosphere, as well as to aid in lessening the vibration of the muffler. This cushion will aid in deadening the sound of the inrushing air to the muffler in the event of a quick closing of the throttle of the automobile, not shown.

A modification of the muffler is shown in Fig. 2. Here the outer cylindrical shell or tube 50 is made in one piece in contradistinction to the plurality of cups described in the former construction. Tube 50 is subdivided by cup or saucer shaped partitions 51, 51, 51, 52 and 53, which are welded to the inner surface of tube 50. The ends are closed also by cup shaped members 55 and 56. An inlet tube 60 is seamed to end member 55 for the admission of the exhaust gases from the engine, not shown, to the muffler. A tube 57 of larger diameter than inlet tube 60 is disposed in the first chamber 61 in alignment with tube 60 and is welded to the inner surface of end member 55. Tube 57 will form an annular pocket at 62 into which some of the exhaust gases will rebound to effect a cushion which will tend to eliminate vibration.

Each of the partitions 51 has projecting therethrough and seamed thereto a conical or funnel shaped member 65 adapted to cause a contraction of the exhaust gases as they pro-

gress from chamber 61 to chamber 66 and from chamber 66 to chamber 67 and from chamber 67 to 68. Partition 52, however, is equipped with a plurality of apertures 69^a for breaking up and segregating the exhaust gases as they progress therethrough into chamber 69. Partition 53 has projecting therethrough and spun thereto an open cylindrical tube 70 in alignment with the other tubes and of the natural progress of the gases. Moreover, a tube 75 of larger diameter than tube 70 projects through and is spun to end member 56. Another tube 77 of larger diameter than tube 75 is spun to the end closing part 78 of tube 75. Tube 77 is open at each end to allow for the escape of the exhaust gases to atmosphere. Furthermore, tube 70 although projecting into tube 75 allows for an annular space at 80, between its outer surface and the inner surface of tube 75, whereby to provide an opening through which some of the exhaust gases will rebound into the annular pocket 81 to form a cushion adapted to lessen the vibration of the muffler and to decrease the noise incident to the exhaust gases escaping to atmosphere through open tube 77.

Having thus described my invention what I claim as new and desire to secure by Letters Patent is as follows:

In a muffler for internal combustion engines, cups having large central apertures formed therein for permitting the exhaust gases to expand, cups having conical shaped members mounted therein for contracting said gases, a pocket formed at one end of said muffler to aid in lessening the vibration and deadening the sound of the exhaust gases, certain other cups having small apertures formed therein to segregate said exhaust gases and another pocket formed at the opposite end of said muffler to aid in lessening the vibration and deadening the sound of the exhaust gases.

In testimony whereof I have affixed my signature.

HERBERT S. POWELL.
